(57) **CLAIM**

The ornamental design for a child-proof eye drop container, as shown and described.

DESCRIPTION

FIG. 1 is a front perspective view of a child-proof eye drop container showing my new design;

FIG. 2 is a front view thereof;

FIG. 3 is an exploded front view thereof, showing the container and the cap comprising the upper turnable component and the base component;

FIG. 4 is a top view thereof;

FIG. 5 is a bottom view thereof;

FIG. 6 is a right side view thereof;

FIG. 7 is a front perspective view thereof, showing the container in a closed state where the upper component of the cap is turned at an angle;

FIG. 8 is a front view thereof, showing the container in a closed state where the upper component of the cap is turned at an angle;

FIG. 9 is a right side view thereof, showing the container in a closed state where the upper component of the cap is turned at an angle;

FIG. 10 is a top view thereof, showing the container in a closed state where the upper component of the cap is turned at an angle;

FIG. 11 is a bottom view thereof, showing the container in a closed state where the upper component of the cap is turned at an angle; and,

FIG. 12 is a bottom perspective view thereof.
